L. S. DENISON.
CARPET STRETCHER.

No. 431,182.

Patented July 1, 1890.

UNITED STATES PATENT OFFICE.

LINUS S. DENISON, OF PENZA, OHIO.

CARPET-STRETCHER.

SPECIFICATION forming part of Letters Patent No. 431,182, dated July 1, 1890.

Application filed November 7, 1889. Serial No. 329,466. (No model.)

To all whom it may concern:

Be it known that I, LINUS S. DENISON, a citizen of the United States, residing at Penza, in the county of Trumbull and State of Ohio, have 5 invented a new and useful Carpet-Stretcher, of which the following is a specification.

This invention relates to carpet-stretchers of that class which are provided with mechanism for driving tacks; and it has for its object to construct a device of this class which shall be simple, durable, and effective, and by means of which a forcible and effective blow may be delivered directly upon the head of the tack, which may thus be driven completely by a single blow.

The invention consists in the improved construction, arrangement, and combination of parts, which will be hereinafter fully described, and particularly pointed out in the 20 claims.

In the drawings hereto annexed, Figure 1 is a perspective view of my improved combined carpet-stretcher and tack-driver. Fig. 2 is a front view, on a larger scale, of the lower portion of the same. Fig. 3 is a side view. Fig. 4 is a vertical sectional view taken on the line $x-x$ in Fig. 2. Fig. 5 is a detail view of the lower end of the tack-feeding tube and feeding mechanism. Fig. 6 is a detail view 25 showing the mechanism illustrated in Fig. 5 in a different position. Fig. 7 is a perspective view, with parts broken away, of the lower end of the device, showing a tack in position to be driven. Fig. 8 is a perspective detail view to 30 show more clearly the links 10 and clamps 11.

Like numerals of reference indicate like parts in all the figures.

1 designates an ordinary wooden handle, which has a perforation 2 extending through 40 its entire length to receive a metallic rod 3, having at its upper end a handle 4, by means of which it may be conveniently manipulated. To the lower end of the handle 1 is secured the stretcher-head 5, which is provided with 45 arms 6 to receive screws or bolts, by means of which they are attached to the lower end of the handle 1. The head 5 is provided with teeth 7, adapted to engage the carpet, when the device is in operation, for the purpose of 50 stretching it and pushing it up close to the wall of a room and hold it in position while the tacks are being driven.

8 designates a sleeve or tubular bearing which is formed above the head 5, and which affords a bearing for the lower end of the vertically sliding or reciprocating rod 3. The front and rear sides of the sleeve or bearing 8 are provided with laterally-extending lugs 9, between which are pivoted links 10, to the lower ends of which are pivotally connected 60 the clamps 11, which serve to hold the tacks in position for driving. The said clamping heads or jaws are provided on their inner sides with tapering grooves 12, adapted to receive and hold the tack in such a manner as 65 to permit the point of the same to project slightly beyond the lower ends of the clamping jaws. The latter are held together in position for operation by means of an annular band 13, of rubber or other suitable elastic 70 material, which shall permit the jaws to separate for the escape of the head of the tack when the latter is driven.

The parts described in the foregoing are so proportioned with regard to size and location 75 that the lower ends of the clamping-jaws shall be normally slightly above the level of the extreme outer ends of the points 7, in order to permit the latter to engage the carpet securely, but without danger of tearing or injuring the same. The longitudinally-sliding rod 3 should, when at the extreme limit of 80 its downward stroke, be permitted to project slightly below the points of the teeth 7.

To the front side of the rod or handle 1 is 85 secured the tack-guide 13^a, which is constructed of a strip of sheet metal, the edges of which are bent so as to form flanges 14, between which a groove 15 is left open to receive the tack. The lower end of the tack-guide 90 is bent or curved rearward, as shown at 16, and terminates in a downward-extending tube 17, in which the lower end of the rod 3 has a bearing. The tube 17 is provided at its upper front end with a slot 18, having forwardly-extending flanges 19, which serve to guide the point of the tack into the lower end of the said tube.

The tack-feeding tube or guide 13 is provided with a laterally-extending bracket 20, 95 upon the upper side of which is pivotally mounted a disk 21, provided at its edge which projects over the groove 15 in the tack-guide 13 with a notch 22. The opposite side of the

disk 21 is provided with perforations 23 24, the upper one of which 23 is connected with the lower end of the coiled spring 25, the upper end of which is attached at 26 to the handle 1 by means of a pin or stud. The lower perforation 24 is connected by a pivoted rod 27 with a latch-plate 28, which is pivotally connected to one of the arms or brackets 6 of the head 5 of the carpet-stretcher. The latch-plate 28, which is normally in an inclined or beveled position, is located in the path of the vertically-reciprocating rod 3, and it normally presses or bears against the side of the latter, being held in contact therewith by the tension of the coiled spring 25. It will be seen that when the reciprocating rod 3 is moved in an upward direction and out of contact with the latch-plate 28 the tension of the coiled spring 25 causes the disk 21 to oscillate upon its pivot, thus moving the notch 22 in a downward direction across the groove 15 of the tack-guide 13. If the latter has been previously filled with tacks, the lowermost tack will be carried by the notch 22 past the disk 21, and be allowed to escape into the tube at the lower end of the tack-guide, which extends down into the tubular sleeve or bearing 8, thus conducting the tack through the latter and down between the clamping-jaws 11, between the lower ends of which the point of the tack will thus be caused to project. The remainder of the tacks will meanwhile remain supported against the periphery of the disk 21. When the reciprocating rod 3 is lowered or forced in a downward direction for the purpose of driving the tack which is held between the clamping-jaws, it engages the pivoted latch-plate 28, thereby causing the disk 21 to be restored to its normal position, with the notch 22 facing in an upward direction and ready to receive the next tack.

From the foregoing description, taken in connection with the drawings hereto annexed, the operation will be readily understood.

The device herein described is exceedingly simple in its construction, and may be manufactured at a slight expense, and by means thereof the carpet may be stretched and held securely while the tacks are being driven one by one in the desired places.

The escapement device, by means of which the tacks are fed one by one to the hammer, and which consists mainly of the pivoted notch or disk 21 and the latch-plate 28 in connection with the coiled spring and the connecting-rod, is exceedingly simple in construction, and will be found to operate with almost absolute certainty. The vertically-reciprocating rod 3, which extends through the entire length of the handle 1, serves as a hammer, and will deliver a direct and forcible blow, whereby the tack which is securely held while being operated upon will be driven with ease and certainty into the hardest flooring.

The device may be operated by any person without previous skill or experience, and it

may be operated without bending or stooping, thus rendering the operation of laying carpets much less tiresome than when the ordinary methods are employed.

Having thus described my invention, what I claim, and desire to secure by Letters Patent, is—

1. The combination, with the longitudinally-perforated handle having the reciprocating hammer-rod, of the stretcher-head having a tubular bearing-sleeve provided with laterally-extending lugs, the links pivoted to said lugs, the clamping-jaws pivoted at the lower ends of said links, and an elastic band encircling the lower ends of the clamping-jaws, substantially as set forth.

2. In a combined carpet-stretcher and tack-driver, the herein-described stretching-head, provided with arms for its attachment to the lower end of a rod or handle, a tubular bearing-sleeve for the reciprocating hammer or tack-driver, the clamping-jaws connected pivotally by means of links to the front and rear sides of said bearing-sleeve, and a tack-guide terminating at its lower end in the tube extending into the said bearing-sleeve, substantially as set forth.

3. The combination, with the longitudinally-perforated handle, of the stretching-head having a tubular bearing-sleeve, the clamping-jaws pivoted to the latter, an elastic band encircling said jaws, and the tack-guide consisting of a grooved guide-strip curved at its lower end and terminating in a tube extending into the bearing-sleeve, and provided at its upper end with a slot and forwardly-extending flanges, substantially as and for the purpose set forth.

4. The combination, with the tack-guide having the laterally-extending bracket, of the notch escapement-disk mounted pivotally upon said bracket, a coiled tension-spring connected with the said escapement-disk, and a pivoted latch-plate connected by a link or rod with the said escapement-disk at a point opposite to the said tension-spring, substantially as and for the purpose set forth.

5. The combination of the tack-guide having rearward-curved lower end terminating in a guide-tube, the reciprocating hammer-rod, the tack-clamping jaws, the pivoted notch escapement-disk, the coiled tension-spring, and a latch-plate located in the path of the reciprocating hammer-rod and connected by a link or rod with the pivoted escapement-disk, substantially as set forth.

6. The combination of the longitudinally-perforated handle, the stretching-head secured to the lower end of the same and having a tubular bearing-sleeve provided with laterally-extending lugs, the links connected pivotally to the latter and having the pivoted clamping-jaws, the tack-guide terminating at its lower end in a guide-tube extending into the tubular bearing-sleeve, the pivoted notched escapement-disk, the coiled tension-spring, the latch-plate connected pivotally to one of

the arms of the stretching-head and lying in the path of a vertically-reciprocating hammer-rod extending through the longitudinally-perforated handle and having a handle at 5 its upper end, and a link or rod connecting said pivoted latch-plate with the escapement-plate, substantially as and for the purpose set forth.

In testimony that I claim the foregoing as my own I have hereto affixed my signature to in presence of two witnesses.

LINUS S. DENISON.
